RUBBER COMPOSITION AND METHOD OF
PRESERVING RUBBERMarion C. Reed, Lakewood, Ohio, assignor to The
B. F. Goodrich Company, New York, N. Y., a
corporation of New YorkNo Drawing. Original No. 1,899,058, dated Febr-
uary 28, 1933, Serial No. 398,104, October 7,
1929. Application for reissue filed December
15, 1933, Serial No. 702,541

28 Claims. (Cl. 18—50)

This invention relates to the art of preserving rubber, either in a vulcanized or unvulcanized condition, and to rubber compositions so preserved.

It is well known that rubber deteriorates more or less rapidly upon aging, especially when exposed to light, heat, or air. It has heretofore been proposed to retard such deterioration by treating the rubber, either before or after vulcanization, with so-called "anti-oxidants" or "age-resistors", such as amino compounds, hydroxy compounds, and aldehyde-amine condensation products.

The present invention, briefly stated, consists in treating rubber with a member of a class of anti-oxidants which has been found to be unusually effective in retarding the deterioration of rubber compositions. This class of compounds includes substances possessing the structural formula

where C_1 and C_2 are terminal carbon atoms of a saturated or unsaturated chain, R is an aromatic nucleus directly attached to the nitrogen atom, and X is a hydroxyl, nitroso, or amino group.

Preferably C_1 and C_2 are the terminal carbon atoms of a saturated chain which may or may not contain other atoms than carbon, the substituents on the various atoms of the chain, and particularly on the terminal carbon atoms C_1 and C_2 , if other than hydrogen, preferably being monovalent radicals which do not contain double bonds, such as alkyl, alkoxy, hydroxy, etc. Substituents containing doubly bound oxygen, such as carboxyl and carbonyl groups, tend to decrease the effectiveness of the compounds as anti-oxidants. The group R may be any aromatic nucleus such as a benzene or naphthalene nucleus. The activity of the compound is somewhat affected by the position of the substituent group X. For example, if R is a benzene nucleus, the compounds containing the substituent X in the ortho position are more active than those in which it occupies the meta position, while compounds in which it takes the para position are still more active.

Although the compounds in which the aromatic nucleus is unsubstituted, or contains other substituents, such as amino or nitroso groups,

are active anti-oxidants, the hydroxy substituted compounds appear to be the most valuable, because of their ease of preparation, great activity as anti-oxidants, and negligible effect on the vulcanization of the rubber.

The following compounds, for example, are typical members of the hereinabove defined class of anti-oxidants:

It will be noted that each of these compounds contains an aromatic nucleus (preferably with a hydroxyl, nitroso, or amino group—including secondary and tertiary amino groups—substituted in the para position) attached to the nitrogen of a heterocyclic ring. That is, the nitrogen which is attached to the aromatic nucleus is likewise attached to both ends of a chain of atoms, the nitrogen together with the said chain constituting a heterocyclic nucleus. No explanation has been found for the peculiar relationship of the molecular structure of the compounds to their anti-oxidant powers, but numerous tests have demonstrated the efficacy of substances possessing this molecular structure.

The substances belonging to the class defined above are extremely effective in retarding the deterioration of rubber. If employed in rubber compositions in the same proportions as most previously known anti-oxidants, they are far more effective, whereas small proportions of these substances are as effective as much larger proportions of previously known substances. They are odorless and do not impart an odor to a vulcanized rubber composition into which they have been incorporated. Many of these substances have practically no effect on the color of rubber, and hence may be employed in white or light-colored compositions without fear of darkening or staining.

Example 1.—As a specific example of one embodiment of the method of this invention, a typical tire tread composition was prepared containing: blended plantation rubbers 100 parts by weight, sulfur 5.5 parts, zinc oxide 30 parts, gas black 40 parts, mineral rubber 10 parts, palm oil 5 parts, and hexamethylene tetramine 0.75 part. This was divided into five portions, one of which was used as a control. To the others were added respectively 0.47, 0.95, 1.90, and 3.80 parts of p-hydroxy N-phenyl morpholine (1/4%, 1/2%, 1%, and 2% of the weight of the composition). The compositions were thoroughly mixed, and vulcanized in a press 45 minutes at 145° C. (294° F.) to produce an optimum cure. The relative rates of aging of the vulcanized compositions were compared by measuring their respective tensile strengths and elongations before and after aging.

75 Accelerated aging tests were carried out in the

Geer aging oven, in which samples were maintained at a temperature of 70° C. (158° F.) in a constantly renewed stream of air, as well as in the Bierer-Davis bomb, in which other samples were maintained at the same temperature (70° C.) in an atmosphere of oxygen at a pressure of 300 lbs. per sq. in. In the table below T indicates ultimate tensile strength in pounds per sq. in. and E indicates ultimate elongation in per cent. of original length.

Aging tests of p-hydroxy N-phenyl morpholine

Proportion of anti-oxidant	Before aging		After 7 days in the Geer oven		After 48 hours in the Bierer-Davis bomb	
	T	E	T	E	T	E
0.....	3250	653	1860	493	690	347
1/4%.....	3400	657	2480	526	1520	470
1/2%.....	3440	650	2990	560	2260	568
1%.....	3500	660	3060	550	2780	597
2%.....	3460	660	3280	590	2950	603

It is evident from the above example that rubber compositions containing even small proportions of this new anti-oxidant resist deterioration far more effectively than similar untreated compositions.

Example 2.—Two compositions were prepared containing the same constituents as the compositions of Example 1 above, except that the first contained no anti-oxidant, while the second contained 2 parts of p-nitroso N-phenyl morpholine as a combined accelerator and anti-oxidant, the hexamethylenetetramine being omitted. The compositions were tested in the manner described in Example 1, after vulcanization for thirty minutes and forty-five minutes at 294° F.

Aging tests of p-nitroso N-phenyl morpholine

Anti-oxidant	Before aging		After 7 days in the Geer oven		After 48 hours in the Bierer-Davis bomb	
	T	E	T	E	T	E
None (vulcanized 30 minutes).....	3475	676	1783	527	925	420
p-nitroso N-phenyl morpholine (vulcanized 30 minutes).....	3441	643	2650	565	2191	537
None (vulcanized 45 minutes).....	3600	623	1802	457	731	280
p-nitroso N-phenyl morpholine (vulcanized 45 minutes).....	3402	580	2590	450	1860	433

It is evident that the rubber vulcanized in the presence of p-nitroso N-phenyl morpholine resists deterioration due to aging to a much greater degree than rubber vulcanized with other accelerators.

Obviously, the practice of this invention is not limited to the specific compositions given above, such compositions being merely illustrative of specific methods of employing the anti-oxidants of this invention. The proportions of the constituents may be varied, or other substances may be substituted therefor, since this invention is applicable to pure rubber or rubber compositions of the most varied nature. The anti-oxidants may also be applied to unvulcanized or vulcanized rubber with good effect on the age-resisting properties of the rubber, such as by applying them to the surface of the rubber, as for example in solution, or in the form of a paste or emulsion.

comprises treating rubber with a compound possessing the structural formula

5

where C_1 and C_2 are terminal carbon atoms of a chain, R is an aromatic nucleus, and X is an amino group.

17. The method of preserving rubber which comprises treating rubber with a compound possessing the structural formula

18

where C_1 and C_2 are terminal carbon atoms of a saturated chain, the atoms constituting the chain containing only monovalent substituents which do not possess double bonds, R is an aromatic nucleus, and X is an amino group.

18. The method of preserving rubber which comprises treating rubber with an N -aryl morpholine containing an amino group substituted on the aromatic nucleus.

19. The method of preserving rubber which comprises treating rubber with p -amino N -phenyl morpholine.

20. The method of preserving rubber which comprises treating rubber with an N -aryl morpholine containing a hydrocarbon substituted amino group in the para position.

21. The method of preserving rubber which comprises treating rubber with a p -arylamino N -phenyl morpholine.

22. The method of preserving rubber which comprises treating rubber with p -phenylamino N -phenyl morpholine.

23. A composition of matter comprising rubber and a compound possessing the structural formula

5

where C_1 and C_2 are terminal carbon atoms of a chain containing only monovalent substituents which do not possess double bonds, R is an aromatic nucleus, and X is an amino group.

24. A composition of matter comprising rubber and a compound possessing the structural formula

15

26

where C_1 and C_2 are terminal carbon atoms of a saturated chain, the atoms constituting the chain containing only monovalent substituents which do not possess double bonds, R is an aromatic nucleus, and X is a hydrocarbon substituted amino group.

25. A composition of matter comprising rubber and an N -aryl morpholine containing an amino group substituted on the aromatic nucleus in the para position.

26. A composition of matter comprising rubber and p -amino N -phenyl morpholine.

27. A composition of matter comprising rubber and an N -aryl morpholine containing a hydrocarbon substituted amino group on the aromatic nucleus.

28. A composition of matter comprising rubber and p -phenylamino N -phenyl morpholine.
